UNITED STATES PATENT OFFICE.

JOHN C. RINGE, OF BRIDGEPORT, CONNECTICUT, ASSIGNOR TO THE SINGER MANUFACTURING COMPANY, A CORPORATION OF NEW JERSEY.

EMBROIDERING-MACHINE.

1,241,022.

Specification of Letters Patent. Patented Sept. 25, 1917.

Application filed July 25, 1914. Serial No. 852,988.

To all whom it may concern:

Be it known that I, JOHN C. RINGE, a citizen of the United States, residing at Bridgeport, in the county of Fairfield and 5 State of Connecticut, have invented certain new and useful Improvements in Embroidering-Machines, of which the following is a specification, reference being had therein to the accompanying drawings.

10 This invention relates more particularly to an improvement in that class of scallop-stitching embroidery machines forming the subject of my Patent No. 1,158,391, dated October 26, 1915; and it has for its 15 objects partly to provide simple and effective means for spreading loops of thread of one of the laterally spaced reciprocating needles beneath the other needle to produce a covering seam by means of the stitching 20 threads only, partly to provide advantageous means for varying the spacing apart of the needles to produce a covering seam of varying width and to provide a strong and effective connection between the needle-actuating 25 crank and two needle-bars reciprocating in unison but relatively movable laterally, and partly to provide a tension device for one of the stitching threads adapted to compensate in its intensity of action thereon 30 for variations in the width of the covering seam so as to insure production of a flat seam without puckering the work.

As preferably constructed, the machine is provided with two needle-bars each carrying 35 a needle coöperating with a common loop-taker, one of said needles being mounted in fixed bearings and the other in a laterally movable needle-frame to which step-by-step movements are imparted by an adjustable link connection with a swinging 40 lever actuated by a controlling cam performing step-by-step rotary movements. The needle-actuating shaft has a crank-pin connected by a link with a tubular stud-pin 45 fixed upon one of the needle-bars and entered by a second stud-pin fixed to the other needle-bar.

The thread of the needle having a laterally fixed rectilinear movement is spread beneath the other needle by means of an oscillating looper adapted to seize such thread between the point of the first-named needle and the work and to distend a loop thereof

laterally in front of the needles for seizure by a spreader which carries it laterally and 55 backwardly for engagement of the upper limb of the loop with the blade of the second needle adjacent the eye while the lower limb of the loop passes beneath the point of the second needle preparatory to its descent 60 through said loop. The said looper and spreader are sustained by independently mounted oscillatory bars journaled in fixed 65 bearings of the bracket-arm and deriving operative movements from independent cams upon the needle-actuating shaft.

The machine is provided with a variable tension device for the covering needle-thread comprising thread-engaging means acted upon by a spring whose degree of compression is varied by a connection with the swinging needle-gate so as to produce a greater tension upon such thread when the needles are close together for production of the narrow portions of the seam than when 75 they are more widely spaced.

The feeding mechanism and presser-foot are preferably given step-by-step sidewise movements whereby the work is fed to the stitch-forming mechanism for production of 80 zigzag or curved covering seams, and the independent lateral movements of one needle relatively to the other provide for suitable 85 variations in the width of the covering seam for production of compound scallops in patterns which are well known in the art.

In the accompanying drawings, Figure 1 is a sectional front elevation of the forward portion of an embroidery machine of the well known Singer type embodying the present improvement, Fig. 2 is a plan of the same, and Fig. 3 a front end elevation of the same with the bed-plate in section and the face-plate of the bracket-arm removed. Fig. 4 is a perspective view of the needle-actuating means and the tension controlling device connected therewith. Figs. 5 and 6 are perspective views showing the needles, the looper and spreader in two stages of their coöperative movements. Fig. 7 represents in detail the needle-reciprocating means. Fig. 8 is a detail sectional view of the variable tension device.

The machine is constructed with a frame comprising the usual bed-plate 1 with 105 bracket-arm formed with the hollow stand-

ard 2 and overhanging member 3 terminating in the head 4 and provided with suitable bearings in which is journaled the main or needle-actuating shaft 5. The primary needle-bar 6 is journaled in fixed bearings in the bracket-arm head 4 and carries the needle 7 which is disposed in laterally spaced relation with the sidewise movable needle 8 carried by the reciprocating needle-bar 9 journaled in bearing bosses 10 of the laterally swinging needle-frame 11. The needle-frame 11 is provided with the alined fulcrum-pins 12 which are suitably journaled in the bracket-arm head 4 to permit the lateral movement of the needle-bar 9 toward and from the needle-bar 6.

The needle-bar 6 has fixed thereon by means of the set-screw 13 the laterally projecting arm 14 having an opening 15 through the same embracing the needle-bar 9 and provided with a depending lug 16 carrying the laterally projecting tubular stud-pin 17 which is embraced by the tubular boss 18 at the lower end of the link 19 having the tubular boss 20 at its opposite end embracing the shouldered crank-pin 21 upon the take-up cam-cylinder 22 fixed upon the forward end of the main-shaft 5. The tubular stud-pin 17 has slidingly fitted therein the stud-pin 23 which is formed with a head 24 having a transverse aperture 25 loosely embracing the needle-bar 9 and an intersecting transverse aperture 26 within which is fitted the plug 27 apertured to admit the needle-bar 9 to which it is secured by means of the set-screw 28. Through the means just described, the needle-bars are reciprocated in unison by a connection with the common actuating crank element and link and are permitted to have relative lateral movement.

The boss 18 is reduced at its outer end to receive the anti-friction roller 29 which moves in the vertical guiding groove 30 in the bracket-arm head 4 to prevent the turning of the needle-bars in the operation of the machine.

Coöperating with the needles in the production of stitches is the oscillating shuttle 31 mounted in the shuttle-race 32 beneath the bed-plate and actuated by means of the driver 33 operatively connected by means including the pitman 34, bellcrank-lever 35 and connecting rod 36 with the actuating crank 37 of the main or needle-actuating shaft.

As represented in my said pending application, the main-shaft has secured thereon a laterally adjustable eccentric 38 connected by the rod 39 with a rocker mounted upon the bearing stud 40 and having an arm carrying the pawl 41 meshing with the ratchet-wheel 42. Rotating with and deriving step-by-step movements from the ratchet-wheel is the pattern-disk 43 formed in its

inner face with the cam-groove 44 which is entered by the stud 45 of the rock-lever 46 having a depending arm connected by the link 47 with the laterally movable feed-dog carrier 48 sustaining the feed-dog 49 and deriving reciprocatory work-advancing and rising and falling movements from usual or suitable means.

Secured upon the rearward face of the ratchet-wheel 42 by screws 50 is the cam-disk 51 provided in its rearward face with the cam-groove 52 which is entered by the roller-stud 53 carried by a lateral lug 54 of the swinging segment-lever 55 having the fulcrum-pin 56 journaled in a suitably apertured bearing lug 57 depending from the bracket-arm member 3. The segment-lever 55 is formed with an undercut slot 55' entered by the similarly shaped head of a stud-screw 60 passing through the end section 58 of the bent link 59 and provided with the clamp-nut 61 by means of which the stud-screw 60 is adjustably secured upon the lever 55. The link section 58 is channeled in its rearward face to receive the extremity of the section 59 which is adjustably secured thereto by means of fastening screws 62 passing through a slot 58' of the section 58 and tapped into the section 59, a washer 62' being interposed between the heads of the screws 62 and the section 58. The eyed opposite extremity of the link section 59 embraces the screw-pin 63 tapped into the lateral ear 64 of the lower bearing boss 10 of the needle-frame. Through the described connections, the needle-bar 9 derives from the cam-groove 52 step-by-step lateral movements toward and from the needle-bar 6.

Journalized in fixed bearings in the bracket-arm head 4 are the vertical oscillatory shafts 65 and 66, arranged in alinement with the needle-bar 6 relatively to the direction of advance of the work; the one positioned in front of the needle-bar 6 and the other rearwardly of the needle-bar 9 relatively to the direction of feed. Secured by means of the fastening screw 67 within a slot of the bar 65 is the shank 68 of the depending and laterally extending hooked looper 69 adapted to move in a segmental path beneath the needle 7. The bar 66 has secured upon its lower end by means of the set-screw 70 the apertured boss 71 of a curved arm 72 having a depending lug 73 to which is secured by screws 74 the shank 75 of the laterally and downwardly extending spreader 76 moving in a segmental path across the forward extremity of that of the looper 69 and transversely to the side of the laterally moving needle and slightly rearwardly thereof.

The bar 65 has secured upon its upper end by means of the set-screw 77 the apertured hub of a crank-arm 78 carrying the ball-stud 79 which is embraced by one end of a connecting rod 80 whose opposite end embraces

a ball-stud 81 upon the upper arm of a rock-lever 82 mounted upon the fulcrum-stud 83 and carrying upon its lower arm the roller-stud 84 which enters the cam-groove 85 of the 5 cam-cylinder 86 fixed upon the main-shaft 5.

The upper end of the bar 66 is similarly provided with the crank-arm 87 carrying the ball-stud 88 connected by means of the rod 89 with a similar ball-stud 90 upon the upper 10 arm of a rock-lever 91 mounted upon the fixed fulcrum-pin 92 and having a depending arm carrying the roller-stud 93 which enters a cam-groove 94 of the cam-cylinder 95 also fixed upon the main-shaft 5. As

15 represented in Fig. 3, the bars 65 and 66 have secured thereon directly beneath the upper bearing member of the bracket-arm head thrust-collars acting in conjunction with the hubs of the crank-arms 78 and 20 87 to restrain them against vertical or end-wise movement while permitting oscillatory movement.

The cam-groove 85 is shaped to impart to the looper 69 a quick movement from a 25 position at the outer side and rearward of the rectilinearly reciprocating needle 7 to a position in advance of the laterally moving needle 8 at which point the loop of needle-thread thus formed is seized by the 30 spreader under the influence of the cam-groove 94 and carried to its extreme lateral and rearward position wherein the upper limb of said loop is engaged by the needle 8 while the lower limb is carried beyond the 35 path of movement of the same and between its blade and the thread leading from its eye to the work preparatory to the descent of the needle 8 through the thread of the needle 7 thus presented to it. The looper immediately moves back to its initial position where it remains immovable until the needles rise for a succeeding stitch, while the spreader performs a corresponding retractive movement into initial position in advance of the 45 needles where it dwells until the succeeding covering needle-thread loop is carried into its path for presentation to the needle 8.

Secured upon the rearward face of the bracket-arm head 4 is a rigid arm 96 having 50 transverse apertures in which are secured by means of the set-screws 97 the axially socketed plugs 98 of the needle-thread tension devices, the upper one of which comprises the opposed dished washers 99 pressed 55 normally together by means of the spring 100 surrounding the threaded stem 101 and interposed between the outer of said washers and the nut 102 applied to said stem, the usual check-spring 103 being housed within 60 the cavity of the plug 98. The lower of these tension devices is of well-known form, and comprises, as represented in Fig. 8, the axially apertured shouldered stud 104, having 65 its reduced rearward end portion secured within an axial aperture of the plug 98 by

means of the set-screw 105, and having its split opposite end portion threaded to receive the thrust-nut 106. Mounted upon the stud 104 exterior to the plug 98 is the tubular hub 107 of the washer 108 upon 70 which are mounted the cupped tension disks 109 between the outer one of which and the nut 106 is interposed the tension spring 110. Within the axial bore of the stud 104 is introduced the push-pin 111 having a cross-bar 75 112 working within the transverse slot of the stud 104 and interposed between the washer 108 and a shoulder of the stud 104.

Secured upon the upper needle-frame fulcrum-pin 12 by means of the set-screw 113 80 is the hub 114 of a crank-arm 115 whose outer end is connected by means of the short link 116 with the depending arm 117 of a tension controlling cam-lever mounted upon the fulcrum stud-pin 118 and provided with 85 an upwardly extending arm 119 formed with a head 120 having an inclined cam-face adapted for engagement with the rounded adjacent end of the push-pin 111. Around the enlarged middle portion of the stud 104 90 and within the socket of the plug 98 is coiled the body of the check-spring 121 which is provided with the usual thread-engaging arm 122.

One of the needle-threads is led from the 95 source of supply between the tension-disks 99 and thence beneath the usual grooved guide-pulley 123 and through one of the eyes of the take-up arm 124 to the laterally moving needle 8, while the other needle-thread is led from its source of supply between the tension-disks 109 and thence beneath the guide-pulley 123 and through the other eye of the take-up arm 124 to the 100 rectilinearly reciprocating needle 7. As the 105 needle-frame 11 performs its lateral step-by-step movements, it communicates to the cam-lever 117 119 rocking movements through the described connections from which the axial push-pin 111 derives operative movements in thrusting the tension-disks 109 toward the nut 106 and thereby 110 compressing the tension-spring 107 to vary the drag upon the thread leading to the 115 needle 7.

As described more fully in my said patent, the presser-bar 125 sustains upon its lower end the sidewise movable presser-foot 126 rearward of the needles and the spring 120 smoothing-plate 127 and cord-guiding strip 128 in advance thereof.

In the operation of the machine, the needles descend through the work, and as their points emerge therefrom the thread of the needle 7 is seized by the looper and 125 passed in the form of a loop to the spreader which presents it distended for passage by the needle 8 in its succeeding descent. As the stitching progresses, the work is advanced and simultaneously moved sidewise 130

step-by-step to produce a curved seam which is varied in width according to the pattern determined by the shape of the cam-groove 52 by the step-by-step sidewise movement of the needle 8. The rocking of the needle-frame causes the actuation of the cam-lever arm 119 which acts through the push-pin 111 to vary the compression of the spring and hence correspondingly vary the drag 10 upon the thread of the needle 7 by means of which, in conjunction with the action of the take-up, the covering needle-thread is maintained taut in each stitch so as to produce a flat seam but without drawing the fabric sufficiently to pucker it.

When it is desired to produce a covering seam of uniform width, the stud-screw 60 is shifted into neutral position in alinement with the fulcrum-pin 56 in which position 20 the needle-frame link 58 59 is maintained against operative movement and the needle-frame is held stationary. The spacing of the needles apart under such condition may be adjusted by loosening the screws 62 and 25 adjusting the link section 59 endwise of the section 58.

While the present improvement is herein shown and described in connection with the machine forming the subject of my previously mentioned patent, it is obviously adapted for embodiment in other types and varieties of machines, the various features of the improvement being adapted for individual employment without the others, and 35 being susceptible of considerable modification in the construction and arrangement of the component parts without departure from the scope of the invention.

Having thus set forth the nature of the invention, what I claim herein is:—

1. In a sewing machine, the combination with stitch-forming mechanism comprising a plurality of laterally spaced reciprocating needles, of a looper adapted to seize the 45 thread of one needle at one side of the work and carry a loop thereof laterally, a spreader adapted to seize said thread-loop from the looper and present it for passage of the other needle at the same side of the work, oscillatory bars fixed against endwise movement and sustaining respectively said looper and spreader, and means for imparting to said bars operative movements.

2. In a sewing machine, the combination with stitch-forming mechanism comprising a plurality of laterally spaced reciprocating needles, of a looper adapted to seize the 55 thread of one needle at one side of the work and carry a loop thereof laterally, a spreader 60 adapted to seize said thread-loop from the looper and present it for passage of the other needle at the same side of the work, oscillatory bars mounted in fixed bearings parallel with the direction of thrust of the needles 65 and sustaining respectively said looper and

spreader, and means for imparting to said bars differentially timed operative movements.

3. In a sewing machine, the combination with stitch-forming mechanism comprising 70 a plurality of laterally spaced reciprocating needles, of a looper adapted to seize the thread of one needle at one side of the work and carry a loop thereof laterally, a spreader adapted to seize said thread-loop from the looper and present it for passage of the other needle at the same side of the work, oscillatory bars mounted in fixed bearings and sustaining respectively said looper and spreader, means for imparting to said bars 75 differentially timed operative movements, and means for imparting to the last-named needle step-by-step lateral movements toward and from the other needle.

4. In a sewing machine, the combination 85 with a rectilinearly reciprocating needle-bar mounted in fixed bearings and carrying a needle, of a laterally jogging needle-frame, a reciprocating needle-bar journaled therein and carrying a needle, loop-taking devices, 90 common means for reciprocating said needle-bars, and means sustained independently of said rectilinearly reciprocating needle-bar and of the bearings therefor for imparting to the needle-frame a plurality of step-by-step lateral movements in the same direction.

5. In a sewing machine, the combination with a reciprocating needle-bar mounted in fixed bearings and carrying a needle, of a laterally jogging needle-frame, a reciprocating needle-bar journaled therein and carrying a needle, spreader mechanism adapted to seize a loop of one needle-thread and present it for passage of the other needle at the same side of the work, loop-taking devices, 100 common means for reciprocating said needle-bars, jogging means including an actuating element and a reciprocatory element in constant operative relation therewith, for imparting to the needle-frame step-by-step 105 lateral movements, means for rendering said jogging means ineffective, and means whereby the spacing apart of said needles may be adjusted.

6. In a sewing machine, the combination 115 with a rectilinearly reciprocating needle-bar and a laterally movable reciprocating needle-bar each carrying a needle, and means for imparting lateral movements to the second-named needle-bar, of an actuating crank-element, a tubular stud-pin rigidly secured to one of said needle-bars, a stud-pin carried by the other of said needle-bars and entering said tubular stud-pin, the axes of said stud-pins substantially intersecting the axes 120 of the needle-bars, and a link connection 125 between said crank-element and one of said needle-bars.

7. In a sewing machine, the combination with a rectilinearly reciprocating needle-bar 130

and a laterally movable reciprocating needle-bar each carrying a needle, and means for imparting lateral movements to the second-named needle-bar, of an actuating crank element, a tubular stud-pin rigidly secured to the rectilinearly reciprocating needle-bar, a link connection between said crank element and stud-pin for reciprocating said needle-bar, and a stud-pin carried by the laterally 5 movable needle-bar and entering said tubular stud-pin.

8. In a sewing machine, the combination with a rectilinearly reciprocating needle-bar and a laterally movable reciprocating needle-bar each carrying a needle, and means for imparting lateral movements to the second-named needle-bar, of an actuating crank-element, a rigid arm fixed to the rectilinearly reciprocating needle-bar and 15 apertured to embrace the laterally movable needle-bar and carrying a tubular stud-pin, a link connection between said crank element and stud-pin, and a stud-pin carried by the laterally movable needle-bar and 20 25 slidingly fitted within said tubular stud-pin.

9. In a sewing machine, the combination with a rectilinearly reciprocating needle-bar and a laterally movable reciprocating needle-bar each carrying a needle, and means 30 for imparting lateral movements to the second-named needle-bar, of an actuating crank-element, a tubular stud-pin rigidly secured to the rectilinearly reciprocating needle-bar, a link connection between said crank element 35 and stud-pin for reciprocating said needle-bar, a transverse plug apertured to fit the laterally movable needle-bar, means for securing it in position, and a second stud-pin entering said tubular stud-pin and provided with 40 a head transversely apertured to fit said plug and to embrace the needle-bar to which it is secured.

10. In a sewing machine, the combination with stitch-forming mechanism comprising 45 a plurality of reciprocating needles, means for producing between them relative lateral movements, and means whereby thread is laid between said needles upon the work in the production of stitches, of a needle-thread tension device, and means for vary- 50

ing the intensity of action of the tension device upon the thread proportionately with the lateral spacing apart of said needles.

11. In a sewing machine, the combination with stitch-forming mechanism comprising 55 a plurality of reciprocating needles, side-shifting means for imparting to one of said needles step-by-step lateral movements toward and from the other needle, and means whereby thread is laid between said needles upon the work in the production of stitches, of a needle-thread tension device, and means connected with said side-shifting means for varying the action of said tension device upon the thread of one of said needles. 60 65

12. In a sewing machine, the combination with a reciprocating needle-bar mounted in fixed bearings and carrying a needle, a laterally jogging needle-frame, and a reciprocating needle-bar journaled in said needle-frame and carrying a needle, of a tension device, a crank-arm rigidly connected with said needle-frame, and means connected with said crank-arm for controlling the intensity of action of the tension device upon the thread leading to one of said needles. 70 75

13. In a sewing machine, the combination with a reciprocating needle-bar mounted in fixed bearings and carrying a needle, a laterally jogging needle-frame, and a reciprocating needle-bar journaled in said needle-frame and carrying a needle, of a tension device comprising thread-engaging means, a spring acting thereon to produce a drag 80 85 upon the thread, an endwise movable pin acting upon said spring to vary its normal degree of compression, a cam-lever acting upon said pin, a crank-arm rigidly connected with said needle-frame, and an operative connection between said cam-lever and said crank-arm. 90

In testimony whereof, I have signed my name to this specification, in the presence of two subscribing witnesses.

JOHN C. RINGE.
